UNITED STATES PATENT OFFICE

SAMUEL N. COULTER, OF LOS ANGELES, CALIFORNIA

CLASP FOR GARMENT SUPPORTS

Application filed August 20, 1930. Serial No. 476,503.

This invention relates to buckles or clasps intended to be used in connection with a garment supporter, and while the clasp may be used for different specific purposes, in the present specification it is illustrated as applied to the lower edge of a girdle, for supporting the upper end of a garter.

As usually constructed, a clasp of this type comprises two hinged jaws that are controlled or held in their gripping position by means of a lever or lever plate. This lever plate increases the thickness of the clasp and makes it bulky, and this detracts from its usefulness and attractive appearance.

The general object of this invention is to provide a clasp of simple construction that will overcome this objection.

A further object is to provide a clasp so constructed that the pull upon it holds the jaws in their gripping position, but which may be readily released by a simple movement of the parts.

A further object of the invention is to produce a clasp of this kind that will present smooth, substantially flat and unobstructed faces; also to provide a clasp of simple construction that can readily be attached to the lower edge of a girdle without the use of stitching or any metal fastening parts carried on the girdle.

Further objects of the invention will appear hereinafter.

The invention consists of novel parts and combination of parts to be described herein-after, all of which contribute to produce an effective clasp for garment support.

A preferred embodiment of the invention is described in the following specification, while the broad scope of the invention is pointed out in the appended claims.

In the drawing:

Fig. 1 is a side elevation showing the lower edge of a girdle broken away and illustrating a clasp embodying my invention attached to it and supporting a garter, the lower portion of which is broken away.

Fig. 2 is an edge elevation of the clasp and upper position of the garter.

Fig. 3 is a vertical section through the clasp showing the jaws in their gripping position.

This view is upon an enlarged scale and further illustrates details of its construction.

Fig. 4 is a view similar to Fig. 3 but showing the jaws in their released or open position.

According to my invention, I provide two relatively movable jaw plates preferably hinged together; a link cooperates with these jaw plates so that the pull of the link forces the jaws of the plates together. By forcing the link up, the jaws become released.

Referring more particularly to the parts, 1 represents a main jaw plate having a jaw 2 at one end and having a hook 3 at its lower end forming a rudimentary socket 4 to receive the rigid bar 5 of a horizontally elongated link 6 made of metal or other rigid material.

Opposed to the jaw plate 1 I provide a second jaw plate 7 having a jaw 8 at one end with teeth 9 along its edge.

The jaw plates are relatively flat plates hinged together on a hinge pin 10 that extends through overlapping integral ears 11 formed on the plates. The jaw-plate 7 has an extension 12 that projects into the socket 4, and in the closed, or gripping, position of the jaws, this extension is engaged by the bar 5 and forced outwardly toward the bill 13 of the hook. This holds the jaws pressed tightly together.

Located just above the bar 5, see Fig. 3, the extension 12 has a rounded shoulder 14 that projects out into the socket and operates as a yielding detent to retain the bar 5 in the socket.

In order to release the jaws and cause them to open, it is merely necessary to force the link 6 upwardly; as soon as the bar 5 passes the rounded shoulder 14, it passes up into the space or throat 15 that is constantly open, between the plates and just below the hinge pin, thereby leaving the socket unobstructed, so that extension or tail 12 can swing over against the inner face of the plate 1.

A spring preferably in the form of a leaf spring 16 bent around the hinge pin 10 is provided for holding the jaws open.

The link 6 supports the strap or band 17.

that carries a hose clasp (not illustrated) at its lower end.

In Fig. 1, I illustrate the clasp attached to the lower edge 18 of a girdle. The upper edge 19 of the jaw 8 is preferably rounded as indicated in Fig. 1. This enables the teeth to apply themselves to the cloth of the girdle out of line with each other and distributes the strain more than when the 10 teeth are all in the same horizontal line.

The plates should be composed of thin sheet metal having considerable resiliency. The spring effect in the plate 7 is due to the presence of the bend in the plate that forms 15 the shoulder 14. A similar opposite curve 20 is formed in this plate that also tends to increase its effect as a spring and enables considerable pressure to be developed between the jaws without danger of breaking 20 the outer plate.

It is understood that the embodiment of the invention described herein is only one of the many embodiments this invention may take, and I do not wish to be limited in the 25 practice of the invention, nor in the claims, to the particular embodiment set forth.

What I claim is:—

1. A pair of relatively movable opposed 30 rigid jaws, one of said jaws having a rigid open socket, a link having a rigid bar exerting its pull against the bottom of said socket and capable of being passed freely in and out of said socket, the other jaw having an extension lying in said socket and engaging 35 said bar to hold the jaws together, and a spring urging the jaws toward their open position.

2. A jaw plate having a hook at one end and a jaw at the other end, a jaw plate 40 hinged to the first named plate and having a tail projecting into the hook, and a link in the hook having a locking position in which it presses against the tail to hold the jaws of the plates together, said tail having a 45 shoulder cooperating with the link as a yielding detent to retain the link in the hook.

3. A jaw plate having a hook at one end and a jaw at the other end, a jaw plate hinged 50 to the first named plate and having a tail projecting into the hook, and a link in the hook pressing against the tail to hold the jaws of the plates together, said tail having a shoulder operating as a yielding detent to retain the link in the hook, and a spring between the jaw plates for holding them apart when in their released relation.

Signed at Los Angeles, Cal., this 15th day of August, 1930.

SAMUEL N. COULTER.
